UNITED STATES PATENT OFFICE.

LEO GREGORY McKELLOPS, OF ST. LOUIS, MISSOURI.

CAN OPENER.

Application filed July 5, 1922. Serial No. 572,864.

To all whom it may concern:

Be it known that I, LEO GREGORY McKELLOPS, a citizen of the United States, residing at St. Louis, Missouri, have invented a certain new and useful Improvement in Can Openers, of which the following is a full, clear, and exact description, such as will enable others skilled in the art to which it appertains to make and use the same.

10 This invention relates to can openers of the type that comprise a shank provided with a prong that is adapted to be forced through the center of a can head, and an adjustable cutting blade on said shank that is 15 adapted to be forced downwardly through the can head so as to make a segmental or ring-shaped cut in the can head when said shank is rotated.

The main object of my invention is to provide a can opener of the general type referred to which is so constructed that the cutting blade can be adjusted easily into various positions and locked securely in adjusted position without the necessity of manipulating a screw or similar retaining device.

Another object is to provide an inexpensive and easily adjustable can opener which is so constructed that there is no possibility 30 of the cutting blade slipping during the operation of removing a can head or forming a hole therein.

To this end I have devised a can opener that comprises a shank, a cutting blade slidably mounted on said shank and a means that is rendered operative by the engagement of the cutting blade with the can head for securely locking said cutting blade in adjusted position and which is rendered inoperative by gravity, thereby automatically releasing the blade, when the shank is moved upwardly at the completion of the cutting operation to disengage the blade from the can head.

45 Figure 1 of the drawings is a side elevational view of a can opener constructed in accordance with my invention; and

Figure 2 is a top plan view of said can opener.

50 Referring to the drawings which illustrate the preferred form of my invention, A designates the shank of my improved can opener which preferably consists of a flat metal bar or member provided at one end 55 with a handle B and provided at its opposite end with a prong C that is adapted to be

forced through the center of the head of a can which it is desired to open. A cutting blade D, which may be of any preferred form, is slidably mounted on the shank A in such a manner that it can be adjusted towards and away from the prong C to vary the diameter of the hole formed in the head of the can by the cutting blade D. In the form of my invention herein illustrated the blade D is provided with a substantially channel-shaped carrier D' slidably mounted on the under side of the shank A and provided at its outer end with a cross bar 1 that extends across the top side of the shank so as to prevent the carrier from dropping off the shank, but still permit it to be adjusted easily longitudinally of the shank and thereafter securely locked to the shank by rocking it into engagement with the shank.

Means is provided for securely locking the blade D in any one of a number of different positions, and while said locking means may be formed in various ways without departing from the spirit of my invention, I prefer to provide the blade carrier D' with a pin or projection 2 and provide the shank with a plurality of holes, notches or recesses 3 arranged in longitudinal alignment with each other different distances from the prong C, and adapted to co-operate with said pin to lock the blade carrier to the shank A. The cross bar 1 is preferably arranged at the rear end of the blade carrier D' so that the normal tendency of said carrier is to swing or rock downwardly into such a position that the pin 2 thereon is out of engagement with the shank A, as shown in broken lines in Figure 1.

In using my improved can opener the prong C on the shank A is first forced through the center of the head of the can and the carrier D' is then moved longitudinally of the shank A so as to set the cutting blade D at the proper point on the can head. The shank is then pressed downwardly so as to force the blade D through the head of the can, which operation causes the pin 2 on the carrier to enter one of the holes 3 in the shank, thereby automatically locking the blade carrier to the shank. Thereafter, the shank is rotated so as to cause the blade to form a segmental or ring-shaped cut in the can head. It is impossible for the blade carrier to slip or move longitudinally of the shank relatively to the prong C during the operation of cutting the can head, due to the

fact that the pin 2 on the carrier projects into one of the holes 3 in the shank and is retained therein by the downward pressure which the user naturally exerts on the shank A during the operation of rotating it to cause the blade to form a cut in the can head. At the completion of the cutting operation the user tilts the shank upwardly to disengage the cutting blade from the can head, and as the blade carrier is rockably mounted on the shank, gravity causes said blade carrier to move automatically into a position to disengage the pin 2 from the shank, thereby releasing the blade carrier and permitting it to be moved freely longitudinally of the shank. The blade carrier can be set quickly and easily to cut either a large hole or a small hole by simply tilting or rocking the front end of the carrier D' downwardly and moving the carrier longitudinally of the shank A, so as to arrange the cutting blade the desired distance away from the axis about which the shank A is revolved, the pin 2 on the blade carrier passing upwardly into one of the holes 3 in the shank when the blade is forced downwardly through the can head and remaining seated in said hole during the remainder of the operation of cutting out the head of the can or forming a hole therein. If desired, the carrier D' can be provided intermediate its ends with one or more upwardly projecting lugs 4 that serve as finger pieces on which the user can press downwardly so as to disengage the pin 2 from the shank A preparatory to sliding the carrier D' longitudinally of the shank to set the cutting blade in adjusted position. The particular construction of the blade carrier D' is immaterial and various means can be used for locking said carrier to the shank, so long as the carrier is mounted on the shank in such a manner and the locking means is of such a character that said locking means will be rendered operative automatically by forcing the cutting blade down through the can head and will be rendered inoperative automatically when the shank is raised to disengage the cutting blade from the can head.

With a can opener of the construction above described there is no possibility of the cutting blade slipping during the operation

of removing the head of a can or forming a hole thereon; it is not necessary to loosen a screw-threaded retaining device preparatory to adjusting the cutting blade and thereafter tightening said device after the blade has been set in adjusted position, and still another desirable feature of such a can opener is its low cost of manufacture, due to its simplicity of construction.

Having thus described my invention, what I claim as new and desire to secure by Letters Patent is:

1. A can opener, comprising a shank, an adjustable cutting blade on said shank, and a projection on one of said parts arranged so that it will be moved into locking engagement with the other part to retain the blade in adjusted position by the operation of forcing the blade into the can head.

2. A can opener, comprising a shank, a cutting blade, a carrier for said blade slidably mounted on said shank, and co-operating means on said carrier and shank adapted to be moved into interlocking engagement by downward pressure exerted on said shank during the operation of forcing the blade into the can head, and adapted to be disengaged by gravity.

3. A can opener, comprising a shank, a cutting blade provided with a carrier that is slidably mounted on said shank, and co-operating devices on said carrier and shank that are moved into locking engagement by the pressure applied to the shank during the operation of forcing the blade into the can head, said carrier being mounted on the shank in such a manner that gravity tends to hold said carrier in such a position that said locking devices will not co-operate with or engage each other.

4. A can opener, comprising a shank provided at one end with a prong for the purpose described, a sliding carrier on the underside of said shank provided at one end with a part that extends transversely across the upper side of said shank, a cutting blade projecting downwardly from the free end of said carrier, a pin projecting upwardly from said carrier, and a plurality of spaced holes in said shank adapted to receive said pin.

LEO GREGORY McKELLOPS.
